DESIGN FOR A BIER PIN

Earl L. Schofield, Rockford, Ill., assignor to Superior Coach Corporation, Lima, Ohio, a corporation of Ohio

Application June 28, 1946, Serial No. 131,134

Term of patent 14 years

(Cl. D19—1)

To all whom it may concern:

Be it known that I, Earl L. Schofield, a citizen of the United States and resident of Rockford,
in the county of Winnebago and State of Illinois,
have invented a new, original, and ornamental Design for a Bier Pin, of which the following is a specification, reference being had to the accompanying drawing, forming a part thereof.

In the drawing:

Figs. 1 and 2 are different side elevations of a bier pin showing my new design, and Fig. 3 is an outer end view thereof.

I claim:

The ornamental design for a bier pin, substantially as shown.

EARL L. SCHOFIELD.
